AXLE FOR DOLL EYES

Lazurus W. Pollack, New York, N. Y.

Application May 29, 1940, Serial No. 337,761

7 Claims. (Cl. 46—169)

This invention relates to new and useful improvements in an axle for supporting doll eyes.

More specifically, the invention proposes the construction of an axle which will flexibly hold the doll's eyes and which will give a minimum amount of trouble to install. The invention particularly proposes to improve a certain type of axle in which certain parts are spot welded together and which cause annoyance in manufacture due to the fact that the welded parts often break open when attempts are made to properly adjust the eyes.

More specifically, the invention proposes the construction of an axle for dolls' eyes which will support each eye so that it is free to move laterally and so that it may be turned into proper position and maintain its turned location.

Still further the invention proposes to characterize the axle by a plate intended to be mounted across the back of a semi-spherical shell of the doll's eye, a sheet metal member of a particular construction slidably associated with the plate and formed with a particular type of socket for an axle rod, and an axle rod engaged in said socket for supporting the eye.

Another object of the invention is the construction of a device as described which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a plan view of a pair of doll's eyes with an axle constructed in accordance with this invention.

Fig. 2 is a fragmentary rear elevational view of one of the eyes illustrated in Fig. 1 looking in the direction of the line 2—2 of Fig. 1.

Fig. 3 is a perspective enlarged detailed view of the plate shown in Fig. 2.

Fig. 4 is a fragmentary perspective detailed view of the sheet metal member and axle of the eye.

Fig. 5 is a developed view of the sheet metal member shown in Fig. 4.

Fig. 6 is an enlarged sectional view taken on the line 6—6 of Fig. 2.

Fig. 7 is an enlarged sectional view taken on the line 7—7 of Fig. 2.

Fig. 8 is a rear elevational view of one of the

eyes of a doll, constructed in accordance with a modification of this invention.

Fig. 9 is an elevational view looking in the direction of the line 9—9 of Fig. 8.

Fig. 10 is an enlarged sectional view taken on the line 10—10 of Fig. 8.

The axle for dolls' eyes, in accordance with this invention, is intended for doll eyes which include a pair of semi-spherical doll eye shells 10 connected with the conventional axle rod 11. Since each eye is of identical construction the details of but one eye will now be given.

A plate 12 is mounted across the back of the doll eye shell 11 and has a narrow elongated slot 13 extended inwards from one end thereof. A lug 14 projects upwards from one end of the plate 12. This lug has an opening 15. A prong 16 projects from one edge of the shell 10 and is engaged through the opening 15 to support one end of the plate 12. The other end of the plate is formed with a pair of projecting portions 17 which engage into socket cutouts 18 formed in an edge of the shell 10. Lug portions 19 are also formed on the edge of the shell 10 and are bent over portions of the end of the plate 12 to firmly secure this end of the plate 12.

A sheet metal member 20 has a tubular bent central portion 20a forming a socket for the axle 11. This tubular bent central portion 20a is of a larger diameter than the width of the slot 13 so that when engaged beneath the slot longitudinally thereof it acts as a slide element capable of sliding along the length of the slot 13 without passing through the slot. The sheet metal member 20 also has side walls 20b and 20c continuing from the tubular portion 20a and extending up through the slot 13. One of the side walls, namely, the side wall 20b has a bent down portion 20bb engaging over the edge of the side wall 20c for securely connecting the walls together as a unit. The bent down portion 20bb also has a pair of prongs 21 on the opposite edges thereof bent laterally in opposite directions and engaging the top face of the plate 12.

The bottom edge 20' of the downwardly bent portion 20bb also engages the top face of the plate 12. The edge 20' and the prongs 21 serve to slidably hold the sheet metal member 20 on the plate 12. The sheet metal member 20 is of a shorter length than the length of the elongated slot 13. Thus the eye shell 10 is capable of moving axially of the axle rod 11. The axle rod 11 is forced into the socket formed by the tubular bent central portion 20a of the sheet metal member. Friction is depended upon to firmly hold

these parts together. However, it is possible to turn the eye shell 10 so that it turns on the axle 11. In this manner the eyes may be properly aligned in the eye sockets.

The shell 10 is formed with an opening 22 extended inwards from an edge thereof through which the axle 11 passes.

Fig. 5 illustrates the blank from which the sheet metal member 20 is formed. The central portion of this blank between the lines AB and CD is turned around a rod 11', preferably of a slightly smaller diameter than the axle 11 to form the tubular socket 20a. It is intended that the axle 11 be forced into the tubular socket so that it frictionally maintains the relative position of these parts. The portion of the blank beneath the line CD forms the wall portion 20c. The portion of the blank above the lines AB, but below the prongs 21, forms the wall portion 20b. The portion of the blank between the prongs 21 forms the downwardly bent portion 20bb.

In Figs. 8-10 inclusive a modified form of the invention has been disclosed which distinguishes from the prior form in several respects. It distinguishes in the manner in which the plate 12 is supported on the eye shell 10, and further distinguishes in the way the sheet metal member 20x is constructed and associated with the plate 12.

At one side of the shell 10 is formed with a pair of rearwardly projecting lugs 24 which have a pair of laterally extending prongs 25 which engage through the opening 15 of the lug 14 of the plate 12 to support this end of the plate.

The sheet metal member 20x has a wide tubular bent central portion 20a forming a socket for the axle rod 11 and positioned beneath and along the length of the slot 13 of the plate 12. The tubular central portion 20a has a pair of projecting side walls 20b and 20c which extend up through the slot 13. Means is mounted on these side walls 20b and 20c for securing them together and for engaging the top face of the plate for slidably mounting the sheet metal member 20x on the plate 12. This means comprises rivets 26 engaged through the side walls 20b and 20c. These rivets secure the side walls together. The heads of these rivets engage the top face of the plate 12.

In other respects this form of the invention is similar to the previous forms and like parts are identified by like reference numerals.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. An axle for dolls' eyes, comprising a semi-spherical doll eye shell, a plate mounted across the back of said shell and having a narrow elongated slot, a sheet metal member having a wide tubular bent central portion forming a socket for an axle rod and positioned beneath and along the length of said slot and having side walls continuing through said slot, elements on said side walls for engaging the top face of said plate for slidably mounting said sheet metal member on said plate, and an axle rod forced into said socket and projecting from an opening in the side of said eye shell.

2. An axle for dolls' eyes, comprising a semi-spherical doll eye shell, a plate mounted across the back of said shell and having a narrow elongated slot, a sheet metal member having a wide tubular bent central portion forming a socket for an axle rod and positioned beneath and along the length of said slot and having side walls continuing through said slot, means for securing said side walls together and for engaging the top face of said plate for slidably mounting said sheet metal member on said plate, and an axle rod forced into said socket and projecting from an opening in the side of said eye shell, said means for securing said side walls together including a portion of one of the walls bent over a portion of the other of the walls.

3. An axle for dolls' eyes, comprising a semi-spherical doll eye shell, a plate mounted across the back of said shell and having a narrow elongated slot, a sheet metal member having a wide tubular bent central portion forming a socket for an axle rod and positioned beneath and along the length of said slot and having side walls continuing through said slot, means for securing said side walls together and for engaging the top face of said plate for slidably mounting said sheet metal member on said plate, and an axle rod forced into said socket and projecting from an opening in the side of said eye shell, said means for securing said side walls together including a portion of one of the walls bent over a portion of the other of the walls, and said bent over portion having an edge engaging the face of said plate for assisting in slidably mounting the sheet metal member on the plate.

4. An axle for dolls' eyes, comprising a semi-spherical doll eye shell, a plate mounted across the back of said shell and having a narrow elongated slot, a sheet metal member having a wide tubular bent central portion forming a socket for an axle rod and positioned beneath and along the length of said slot and having side walls continuing through said slot, elements on said side walls for engaging the top face of said plate for slidably mounting said sheet metal member on said plate and comprising laterally bent prongs on said side walls and resting upon the face of said plate, and an axle rod forced into said socket and projecting from an opening in the side of said eye shell, said means for securing said side walls together including a portion of one of the walls bent over a portion of the other of the walls.

5. An axle for dolls' eyes, comprising a semi-spherical doll eye shell, a plate mounted across the back of said shell and having a narrow elongated slot, a sheet metal member having a wide tubular bent central portion forming a socket for an axle rod and positioned beneath and along the length of said slot and having side walls continuing through said slot, one of said side walls being bent down over the other for securing them together and for engaging the top face of said plate, and prongs from said sheet metal member bent laterally in opposite directions and engaging the top face of said plate, and an axle rod forced into said socket and projecting from an opening in the side of said eye shell.

6. An axle for dolls' eyes, comprising a semi-spherical doll eye shell, a plate mounted across the back of said shell and having a narrow elongated slot, a sheet metal member having a wide tubular bent central portion forming a socket for an axle rod and positioned beneath and along the length of said slot and having side walls con-

tinuing through said slot, means for securing said side walls together and for engaging the top face of said plate for slidably mounting said sheet metal member on said plate, and an axle rod forced into said socket and projecting from an opening in the side of said eye shell, said means comprising rivets engaged through said side walls and having their heads engaging the face of said plate.

7. An axle for dolls' eyes, comprising a semi-spherical doll eye shell, a plate mounted across the back of said shell and having a narrow elongated slot, a sheet metal member having a wide, tubular bent central portion forming a socket for an axle rod and positioned beneath and along the

length of said slot and having side walls continuing through said slot, means for securing said side walls together and for engaging the top face of said plate for slidably mounting said sheet metal member on said plate, and an axle rod forced into said socket and projecting from an opening in the side of said eye shell, said plate having an upwardly bent lug, said shell having prongs engaged through an opening in said lug, said shell having cutouts into which portions of said plate extend, and additional lugs from said shell engaging over portions of said plate adjacent the cutout areas of the shell.
